UNITED STATES PATENT OFFICE.

WILLIAM J. REDDEN, OF PHILADELPHIA, PENNSYLVANIA, ASSIGNOR OF FORTY-NINE ONE-HUNDREDTHS TO EDGAR D. HUME, OF COLLINGSWOOD, NEW JERSEY.

SHOE UPPER.

Application filed October 20, 1923. Serial No. 669,653.

To all whom it may concern:

Be it known that I, WILLIAM J. REDDEN, a citizen of the United States, residing at Philadelphia, in the county of Philadelphia and State of Pennsylvania, have invented certain new and useful Improvements in Shoe Uppers, of which the following is a specification.

My invention relates to shoes having ankle bracing means in their uppers.

Prior to my invention the uppers on shoes of the above type were provided with a lining having pockets formed thereon in which stays for supporting the ankle were placed and with flaps sewed to the upper edges of the uppers and overlapping the pockets to prevent the stays in the pockets from coming out. Such construction did not hold the stays in the pockets, but allowed them to double up the flap and protrude from the pockets, thereby forming a hump which dug into the ankle and caused discomfort.

The objects of my invention are to provide a lining for the uppers in which the pockets for the stays are so arranged that the stays may be readily inserted but cannot come out or double up or bulge any part of the lining.

These objects, and other advantageous ends which will be described hereinafter, I attain in the following manner, reference being had to the accompanying drawings in which—

Figure 1 is an inside view of an upper having my invention applied thereto,

Figure 2 a section on line 2—2 of Figure 1,

Figure 3 a section on line 3—3 of Figure 1, and

Figure 4 a modified form of my invention.

Referring to the drawings, 1 indicates an upper having a lining 2 secured thereto by stitching 3. The lining may be mostly cloth as shown in Figure 1 or mostly leather as shown in Figure 4. When the lining is as shown in Figure 1, it is composed of a cloth part 4 having side stays 5 sewed thereto and a top band 6 secured to the cloth part 4 by stitching 7. The side stays and top band are secured to the upper by the stitching 3. A pair of plies 8 are secured to the back of the lining 2 by stitching 9 to form pockets 10 in which ankle supporting stays 11 are

placed. The plies 8 are sewed to the part 4 and the top band 6. The lining is split between the ends of the pockets, as shown at 12, to provide entrance to the pockets 10. The slit 12 is shown in the top band 6 but may be placed in other parts of the lining if desired.

In Figure 4, the cloth part 4^a is sewed to the leather part 6^a by stitching 7^a. In all other respects the construction of the lining is similar to that shown in Figure 1 and I have therefore given corresponding parts 65 similar reference characters with the exponent a.

To insert the supporting stays in the pockets, it is merely necessary to bend the top of the upper outward on the line of the slit 70 and slip the stay into the pocket. When the top of the upper is returned to its normal position the upper part of the pocket will enclose the stay and hold it against displacement as shown in Figure 1. By providing 75 a slit in the lining to form an entrance into the pockets, the lining cannot bulge or double up to form humps because the stitching forming the pockets will always hold the lining in position.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, what 90 I claim as new and desire to secure by Letters Patent is:—

1. A shoe upper provided with stay pockets, each pocket having an entrance opening between its upper and lower end, wherein 95 stays are adapted to extend above and below the entrance opening.

2. A shoe upper having a lining provided with stay pockets and a slit between its ends to form an entrance to the pockets.

3. A shoe upper having a lining; plies sewed to the lining to form stay pockets, the lining being slit between the ends of the pockets to form an entrance thereto.

4. A shoe upper having a lining; a top 105 band sewed to the lining and forming a part

thereof, and plies sewed to the lining and top band to form pockets, the top band having a slit forming an entrance to the pockets.

5. A shoe upper having a lining composed of a cloth part and a slitted leather part sewed thereto, and plies stitched to the lining to form pockets at opposite sides of the slit.

In testimony whereof I have signed my name to this specification in the presence of two subscribing witnesses.

WILLIAM J. REDDEN.
